MINE PROP

Hubert Thines, Brussels, Belgium

Application September 7, 1945, Serial No. 615,099
In Belgium September 8, 1944

10 Claims. (Cl. 248—354)

1

This invention relates to mine props of variable length made of two parts or columns adapted to slide one into the other, the inner column being made fast with respect to the outer column by means of a locking device.

In known types of props, the locking effect whereby the inner column is secured in position is usually obtained by an external action exerted on a set of wedges, or other parts such as eccentrics or links, by means of a bolt or the like and it depends essentially on the strength applied for driving said bolt.

In such props, the inner columns used are generally of upwardly increasing cross-section and this increase in cross-section is made use of to wedge or lock the column after same has been sliding over a distance which sometimes is considerable. The use of an inner column with parallel sides, although cheaper, is not to be recommended, as such a column tends to sink under a relatively low charge without its being possible to prevent it.

Another inconvenience of props of known type is that the locking thereof depends on the driving of a bolt or wedge, although it is desirable to have an automatic lock, i. e. locking that is independent of any external intervention.

These props furthermore do not permit of limiting to a suitable amount the charge carried by the prop so as to avoid its parts being stressed beyond an admissible strain, such as the elastic limit of the metal of which it is made.

The present invention is intended to obviate these inconveniences. To this end, according to this invention, the locking of the inner column with respect to the outer column is effected by means of a three-joint toggle, comprising a locking arm and a counter-arm, which on the one hand have a pivotal engagement with each other, and on the other hand have a pivotal engagement respectively with a movable part engaged by the inner column and with a stationary part bearing on the outer-column. As the inner column moves down, it carries with it the movable part, this rotates the locking lever and thereby automatically locks the said column.

The pivotally supported toggle arms may bear on a supporting member or on each other, through the medium of a bolt, so that by sliding that bolt it is easy to unlock the inner column however high the load on the prop.

The movement of the toggle arms, and consequently the locking strength, may be limited by means of a stop arranged for example under the movable part engaged by the inner column. By

adjusting the position of this stop, it is possible to regulate the locking strength so that it does not exceed an amount compatible with the resistance of the parts of the prop.

5 The accompanying drawings illustrate by means of example some constructional embodiments of the prop according to this invention.

Fig. 1 is a view of the whole prop.

Fig. 2 is a vertical section on line II—II of 10 Fig. 3.

Fig. 3 is a cross-section line III—III of Fig. 1.

Fig. 4 is a vertical section on line IV—IV (Fig. 3).

15 Figs. 5, 6, 7 and 8 show other embodiments in cross-section.

Figs. 9, 10, 11 and 13 show still further embodiments in vertical section, Fig. 12 being a section on line XII—XII of Fig. 10.

20 In the drawings, 1 is the movable inner column and 2 the fixed outer column. The locking device according to the invention comprises the locking arm 3 in pivotal engagement with the shoe 5 which is pressed against the column 1 and in frictional engagement therewith, and the 25 counter-arm 4 in pivotal engagement with the fixed shoe 6 rigid with the outer column 2.

25 In the embodiment according to Figs. 1 to 4, the columns 1 and 2 are of square cross-section. The inner column 1 has parallel sides and the 30 shoe 6 forms part of a locking collar 7 surrounding the column 1 and parts 3, 4 and 5. The arm 3 has semi-circular ends engaged in sockets of like curvature in the shoe 5 and counter-arm 4 and the latter, in turn, rests on a bolt 8 extending through openings 11 of the collar 7 and bears laterally by its semi-circular end in a socket in the stationary shoe 6. The axis of arm 3 forms with the perpendicular to the longitudinal axis of the prop an angle α smaller than the angle 40 of friction.

35 The device arranged as described checks downward movement of the inner column 1 but does not impede its being moved upwardly, so that it is possible to adjust its height.

45 As soon as the column 1 is subjected to a downwardly acting vertical force Q and tends to move downwardly, it carries by friction the shoe 5 which in turn carries the locking arm 3, which rotates about centre O. This rotation causes 50 an increase in the length of the projection of the axis of arm 3 on the perpendicular to the longitudinal axis of the prop, causes a corresponding extension of the collar 7 and generates in said collar tensions equal and opposed to the thrusts 55 P₁ and P₂ (Fig. 2), thus automatically locking

the inner column 1. The rotation of the arm 3 continues until the thrusts P_1 , P_2 reach such value that the friction between the inner column 1 and the collar 7 balances the force Q .

In order that the tensions generated in the parts constituting the prop shall not reach a value incompatible with the resistance of said parts, the movements of shoe 5 and consequently the rotation of arm 3 are limited by a stop 9, which in Fig. 2 is formed by an upstanding edge of the outer column 2. When the shoe 5 comes to rest on said stop, the maximum locking effect is obtained. If this is not sufficient to balance the force Q , the inner column 1 will continue its downward movement.

Instead of being unmoving as shown in Fig. 2, the stop 9 may be separate and made adjustable by suitable means in order to permit of regulating as desired the maximum degree of locking admitted.

Under the locking effect, the arms 3 and 4 exert together a vertical thrust P_3 on the bolt 8. This latter is wedge-shaped, its lower side being inclined so that a longitudinal movement of the bolt causes its upper side to move downwardly, permitting the toggle arms to swing and move the centres O' O'' towards each other about O and instantaneously releasing the lock on column 1.

The initial position of the bolt 8 in its longitudinal direction may be adjusted, thereby permitting of adjusting at will the position of centre O and consequently the size of the angle O' O'' and of the vertical thrust P_3 acting on the bolt. This makes it possible to reduce if desired the force to be applied to the bolt 8 in order to release the lock.

Instead of one set of toggle arms, there may be two or more sets. In the example of Fig. 5 two sets of toggle arms 3, 4 arranged in planes at right angles to each other, act on two adjacent sides of the inner column 1. In the example of Fig. 6, the sets of toggle arms acting on adjacent sides of column 1 are parallel to one another, the shoes 5 being of triangular cross-section.

In Fig. 9 are shown two sets of toggle arms in superposed relation, acting on the same friction shoe 5. In this embodiment the counter-arms 4 rest one on the other and a single bolt 8 is adapted to release the lock.

I have also shown in this example a fixed shoe 6 separate from the collar 7 and bearing thereon through the medium of a wedge 10 adapted to permit of a supplemental adjustment of the angle formed by the axes of the arms 3 and 4.

Figs. 7 and 8 illustrate the invention as applied to props respectively of hexagonal and circular cross-section. In the latter case, the form of the shoe 5 is adapted to surround a sufficient surface of the column 1 to ensure an efficient lock. The arrangement of shoe 6 with an adjustable wedge 10 is also shown in these figures.

Instead of being arranged on one side only of the column 1, the set of toggle arms may embrace the column so that the arms themselves form the locking collar. Two examples of such an arrangement are shown in Figs. 10 and 11.

In the constructional form as shown in Figs. 10 and 12, the counter arm 4 is formed of two elements arranged on either side of the column 1 and resting in the bolt 8 which in turn rests in a side shoulder 12 on column 2. The pivotal engagement between arms 3 and 4 on the one hand, and that between arm 4 and shoe 6 on the other hand, are shown to comprise a pivot, but it is

obvious that they may be of the socket type. The fixed shoe is welded to the upper end of column 2. The operation of this device is identical with that described with reference to Fig. 2.

Fig. 11 shows a modification of the arrangement just described, wherein it is the locking arm 3 that comprises two elements embracing column 1 and resting on bolt 8. In this case also the operation is the same, the locking arm 3 now swinging about the bolt 8.

Other modification may of course be made within the scope of the invention. Thus, instead of resting in a fixed support, the bolt 8 may be interposed between the locking arm 3 and the counter-arm 4 which are then provided, to that end, with projections 13, 14 having notches to engage the bolt 8 as shown in Fig. 13. The movement of bolt 8, as in the preceding instances, results in causing the angle O' O'' to vary according to the principle applied by this invention.

I claim:

1. In a metal mine prop, the combination of an outer column, an inner column slideable in said outer column, means for locking said inner column in said outer column, said locking means comprising a part in frictional engagement with said inner column and movable therewith, a stationary part on said outer column, and a three-joint toggle between said parts comprising a locking arm and a counter-arm, said arms having a pivotal engagement with each other, one of said arms having a pivotal engagement with one of said parts, the other of said arms having a pivotal engagement with the other of said parts, a projection on each of said toggle arms, said projections facing each other, and a wedge-shaped bolt engaged between said projections.

2. In a metal mine prop, the combination of an outer column, an inner column slideable in said outer column, a part in frictional engagement with said inner column and movable therewith, a part rigidly fixed to said outer column, a three-joint toggle between said parts comprising a locking arm and a counter-arm, a wedge-shaped bolt under said toggle arms, one of said toggle arms resting on said bolt.

3. In a metal mine prop, the combination of an outer column, an inner column slideable in said outer column, a shoe in frictional engagement with said inner column and movable therewith, a shoe rigidly fixed to said outer column, a three-joint toggle comprising a locking arm and a counter-arm interposed between said shoes, said arms having each a pivotal engagement with one of said shoes and a pivotal engagement with one another, a wedge-shaped bolt carried by said outer column, said toggle-arms bearing on said bolt.

4. In a metal mine prop, the combination of an outer column, an inner column slideable in said outer column, a shoe in frictional engagement with said inner column and movable therewith, a shoe rigidly fixed to said outer column, a toggle for automatically locking said movable shoe with respect to said fixed shoe as said movable shoe moves downwardly with said inner column, and a removable bolt under said toggle for collapsing same.

5. In a metal mine prop, the combination of an outer column, an inner column slideable in said outer column, a shoe in frictional engagement with said inner column and movable therewith, a shoe rigidly fixed to said outer column, a pair of co-operating toggle arms interposed between

said movable shoe and said fixed shoe, and a stop on said outer column for limiting the downward movement of said movable shoe.

6. In a metal mine prop according to claim 2, one of said toggle arms being yoke-shaped and embracing said inner column.

7. In a metal mine prop according to claim 2, one of said toggle arms being yoke-shaped and embracing said inner column, said yoke-shaped arm resting on said wedge-shaped bolt, a bracket on said outer shaft for accommodating said bolt.

8. In a metal mine prop according to claim 2, means for adjusting the position of said toggle arms with respect to each other independently of said bolt.

9. In a metal mine prop, the combination of an outer column, a collar piece rigidly secured to the top of said column, an inner column slideable in said outer column and collar piece, and means for clamping said inner column against said collar piece comprising a shoe frictionally en-

gaging said inner column and movable therewith, a stationary shoe engaging said collar, a toggle interposed between said movable shoe and said stationary shoe and adapted to exert increasing pressure on said movable shoe as the latter moves downwardly, and a bolt adapted to break said toggle.

10. In a metal mine prop according to claim 9, a wedge interposed between said stationary shoe and said collar piece for adjusting said toggle.
